ASSIGNORS TO ESSEX MOTORS, OF DETROIT, MICHIGAN, A CORPORATION OF MICHIGAN.

VALVE MECHANISM AND VALVE TAPPET THEREFOR.

Application filed June 21, 1921. Serial No. 479,368.

Our invention relates to valve mechanisms for poppet valve-operated internal combustion engines, and the object of the invention is to provide a valve mechanism 5 which shall eliminate most of the noise caused by the valve mechanism. While the invention relates broadly to the valve mechanism, it may be embodied in a more specific form in a valve tappet.

As is well known to those skilled in the art, it is necessary to provide a clearance between the lower end of the valve stem and the top of the valve tappet or adjusting screw to allow for the expansion and contraction of the parts, since otherwise the valve would not seat when the engine is hot. We have ascertained that the noise produced by valve mechanisms of this character is due to the blow struck on the lower 20 end of the valve stem by the tappet adjusting screw. Our invention does away with the noise by reducing the clearance between the parts while at the same time making adequate provision for expansion.

Broadly considered, our invention consists in incorporating in a moving part of the valve mechanism a system of different metals producing differential expansion so that the total length of the parts, considered 30 as a single system, will remain substantially the same throughout the range of working temperatures of the engine. In the preferred embodiment of our invention, the differential system forms a part of the valve tappet, as this has certain practical advantages in manufacture and operation, but we do not limit ourselves to this form.

It will also be understood that under ordinary circumstances it is not necessary to proportion the length of parts with absolute accuracy since very satisfactory results can be obtained without doing so.

The invention will be fully understood from the following description when taken 45 in connection with the accompanying drawings, and the novel features thereof will be pointed out and clearly defined in the claims at the close of this specification.

In the drawing, the figure is a sectional view of the valve mechanism embodying our invention in its preferred form.

Referring now to the drawing, at 11 is shown the cam, at 12 a portion of the engine block, at 13 a valve guide, at 14 a valve spring and at 15 a valve stem, the head be-

ing designated 16. The tappet guide is shown at 17. Within this guide is located a tubular steel tappet 18 of ordinary construction having a mushroom head *a* and a tubular bore *b*. Within the valve tappet 18 is located a tubular interior member or sleeve 19 made of aluminum or some other metal having a relatively high co-efficient of expansion as compared with that of steel. The valve tappet 18 and the aluminum 60 sleeve 19 are pressed together but contact only for a short distance at the outer or top end of the tappet member. The area of contact is designated at *c*. Below this area of contact, there is a clearance *d* between the outside of the aluminum sleeve 19 and the inner wall of the exterior tappet member 18. Mounted in the bore of the aluminum sleeve 19 is a steel sleeve 20 which carries the adjusting screw 21 and an adjusting nut 22, these being of the ordinary construction. There is a slight clearance between the inner diameter of the aluminum sleeve and the steel sleeve 20. This clearance is indicated at *e* in the drawings and 70 is greatly exaggerated for the sake of clearness.

From the foregoing it will be seen that the direction of elongation of the aluminum sleeve due to expansion is opposite to the direction of elongation of the steel parts of the valve mechanism, and since the co-efficient of expansion of the aluminum sleeve is much greater than that of steel, the expansion of one compensates to that extent for 80 the expansion of the other.

In practice, the adjusting screw 21 is set when the motor is cold so that its head makes contact with the lower end of the valve stem but will not lift the valve off its 90 seat. When the engine is hot, it will be found that the valve seats perfectly but that the noise produced by the blow of the tappet adjusting screw on the lower end of the valve is practically eliminated.

What we claim is:

1. A poppet valve mechanism having two separate movable elements arranged for driving connection, one of said elements being composed of a plurality of parts connected to expand in substantially parallel directions and tend to compensate for changes in temperature and thereby substantially maintain a predetermined relation with the other element.

2. A poppet valve mechanism having one of its driven elements composed of a plurality of parts some of which are of metals having different coefficients of expansion, said parts being arranged so that the expansion of one of them tends to compensate that of another.
3. A poppet valve mechanism having one of its moving elements composed of a plurality of parts, said parts being constructed and arranged in substantially parallel relation to cause said element to remain a substantially constant length under the expansion and contraction of the several parts.
4. A poppet valve mechanism having one of its moving elements composed of a plurality of parts some of which are of metals having different coefficients of expansion, said parts being constructed and arranged to cause said element to remain a substantially constant length under the expansion and contraction of the several parts.
5. A poppet valve mechanism having a movable element some of the parts of which are made of steel, and another part of which is made of metal having a higher co-efficient of expansion than steel, the total length of the steel parts being greater than that of the other part, said mechanism being arranged so that the direction of elongation of the steel parts due to expansion will be opposite to that of the part having the higher co-efficient of expansion.
6. A valve tappet comprising three parts two of which are composed of a metal having a relatively low coefficient of expansion and the third of which is of a metal having a relatively higher coefficient of expansion, said parts being arranged with relation to each other so that the elongation of said last named part tends to compensate the elongation of said first named parts.
7. A valve tappet comprising three parts, two of which are steel and the third of which is aluminum, said parts being arranged with relation to each other so that the elongation of the steel parts due to expansion will be in the opposite direction to the elongation of the aluminum part.
8. A valve tappet for the poppet valve of an internal combustion engine comprising a tubular steel exterior member for contact with the cam and an interior steel member for contact with the end of the valve stem and a third member interposed between the said two first-mentioned members and composed of a metal having a greater co-efficient of expansion than steel, the whole being arranged so that the elongation of the intermediate member due to expansion will be in a direction opposite to the elongation of the steel members.
9. A valve tappet comprising a tubular exterior tappet member, an aluminum sleeve located within the bore of said tappet member and secured thereto at the outer end only, and an interior steel member for engagement with the stem of the valve, said interior member being in contact with the aluminum sleeve at the inner end so that the elongation of the aluminum member due to expansion will compensate for the elongation of the steel member.
10. A poppet valve mechanism some of the parts of which are made of steel and another part of which is made of a metal having a higher co-efficient of expansion than steel, said mechanism being arranged so that the direction of elongation of the steel parts will be opposite to that of the part having higher co-efficient of expansion, and the length of the non-steel part being proportioned to the total length of the steel parts so that the elongation of the non-steel part will be substantially equal to the total elongation of the steel parts.

In testimony whereof we affix our signatures.

STEPHEN I. FEKETE.
RALPH H. WHISLER.
